STRANDING MACHINE

Albert G. Harmon, South Bend, Ind., assignor to
 National-Standard Company, Niles, Mich., a
 corporation of Michigan

Application August 9, 1948, Serial No. 43,183

11 Claims. (Cl. 57—58)

1
 My present invention relates to an improvement in wire stranding machines, and more particularly to machines of the type in which a plurality of wires are laid together without twisting thereof to form a strand.

Stranding machines are well known in the art, and essentially comprise a tubular rotor having cradle means journaled therein, and which cradle means provide for the support of supply spools of wire to be stranded. The conventional arrangement for many years has been to support suitably the tubular rotor for rotation about a horizontal axis with the cradle means being arranged to be restrained against rotation with the rotor by the force of gravity, so that the wires drawn off the supply spools are layed over each other by rotation of the rotor by means of a stranding head rotatable with the rotor. A departure from the conventional form of horizontal strander is disclosed in the copending application of Robert C. Pierce, Serial No. 745,913, filed May 3, 1947, which application is assigned to the assignee of my instant application. In the application referred to a tubular rotor is arranged with its axis of rotation extending vertically to provide what may be termed a vertical strander, and the chief advantage of which over a horizontal strander resides in its requirement of substantially less floor space. The vertical arrangement is made possible, as taught in the application last referred to, by the provision of magnetic means for a spool cradle and cooperating magnetic means carried by a stationary part of the frame spaced outwardly of and in alignment with the magnetic means of the spool cradle to prevent rotation of the cradle as the wire is being drawn off the supply spool journaled in the cradle. A further improvement in a vertical strander is disclosed in my copending application, Serial No. 22,072, filed April 20, 1948, in which in the construction therein disclosed a single cradle is arranged to provide for the support of a pair of spools of wire and an important advantage of which resides in a more compact arrangement of and reduction of the number of parts to the end of providing a machine of less vertical height, as well as one which is more economic to manufacture.

In the several machines above referred to, the rotatable rotors impose limitations on the speeds at which the machines may be safely operated due to inertia characteristics of the rotors, and further, if operated at excessive speeds the tubular rotors are subject to undue strain and, in fact, may be distorted so that the machines do not

operate satisfactorily at high speeds. Slowing down of the machines to safe operating limits sacrifices the production of linear feet of strand for a given time and, furthermore, in the event a wire from one of the supply spools breaks, it is difficult to bring the rotor to a stop without entangling of the broken wire about the machine.

It is an object of my present invention to provide a machine of the character described in which the aforementioned tubular rotor is dispensed with to avoid the above noted and other problems involved in the rotation of a tubular rotor at high speeds.

In order to achieve the aforesaid object, I propose to provide upper and lower rotor members which are driven in synchronism in any suitable manner. In such an arrangement the upper and lower rotor members may be of lightweight, so as to avoid the aforementioned objectionable inertia and other problems of the previously known forms of rotors. The upper and lower rotor members of my invention provide for journaling of the opposite ends of cradle means for one or more spools of wire. The construction referred to has an additional advantage in that the cradle means is readily accessible for the replacing of exhausted spools with fresh spools of wire which at present is provided for by the formation of hand openings in the known forms of tubular rotors.

In the preferred form of my invention, the upper and lower rotor members are mounted for rotation about a common vertical axis and provide for the support of the cradle means with its axis extending vertically in alignment with the common axis of the rotors to provide a vertical type of machine having the previously noted advantage of such arrangement over the usual horizontally disposed rotors and cradles.

The above and other objects and advantages of my invention will appear from the following detailed description.

Now in order to acquaint those skilled in the art with the manner of constructing and utilizing wire stranding machines in accordance with my invention, I shall describe in connection with the accompanying drawings certain preferred embodiments of my invention:

Figure 1 is a side elevational view of a portion of a stranding machine embodying my invention;

Figure 2 is an end elevational view of the portion of the apparatus shown in Figure 1, partly broken away and shown in section and illustrating the upper and lower rotor members, the cradle means, and the manner in which the cradle means

is journalled in the upper and lower rotor members.

Figure 3 is a detail horizontal sectional view taken substantially along the line 3—3 of Figure 1, looking in the direction indicated by the arrows, and illustrating primarily permanent magnet means provided for preventing rotation of the cradle of the machine;

Figure 4 is a plan view of the upper rotor member of the machine of Figures 1 and 2;

Figure 5 is a detail vertical sectional view taken substantially along the line 5—5 of Figure 4 looking in the direction indicated by the arrows;

Figure 6 is a bottom view of the upper rotor member of the machine of Figures 1 and 2;

Figure 7 is a detail fragmentary vertical sectional view taken substantially along the line 7—7 of Figure 6 looking in the direction indicated by the arrows;

Figure 8 is a largely diagrammatic side elevational view with certain parts being broken away and shown in section of another embodiment of my invention;

Figure 9 is a detail vertical sectional view taken substantially along the line 9—9 of Figure 8, looking in the direction indicated by the arrows; and

Figure 10 is a detail vertical sectional view taken substantially along the line 10—10 of Figure 9, looking in the direction indicated by the arrows.

Referring now to the drawings, I have shown in Figure 1 a portion of one form of a stranding machine in which my invention is embodied. The stranding machine of this embodiment of my invention includes frame means indicated generally at 8 comprising a main frame, partially shown at 9, and a sub-frame 10. It will be understood that the main frame 9 further comprises a suitable base structure for supporting the machine on the floor and only that part of the main frame necessary to an understanding of my invention is shown in the drawings. The main frame 9, as shown in Figures 1 and 3, is provided with a vertically extending reinforcing rib 11 at the opposite ends of which integral boss portions 12 and 13 are provided for supporting and rotatably mounting a vertically extending drive shaft 14. The drive shaft 14 has upper and lower pulleys 15 and 16 of identical size and shape secured thereto, and a drive pulley 17 is secured adjacent the lower end of the drive shaft 14 below the pulley 16. A belt 17' is trained about the pulley 17 and the belt 17' is adapted to be driven by an electric motor (not shown) for rotating the drive shaft 14 and the pulleys 15 and 16.

The sub-frame 10 comprises a vertically extending U-shaped portion 18 and is mounted to extend laterally of the main frame 9 by means of a plurality of screws 19 threaded in the U-shaped portion 18, and the shanks of which screws pass through horizontally extending slots 20 formed in bracket members 22 which are secured to the main frame 9 as by the screws 23. The U-shaped portion 18 provides for the passage therethrough of the drive shaft 14 and the screws 19 provide for rigidly supporting the sub-frame 10 in adjusted position laterally of the main frame 9 by sliding movement in the slots 20 of the brackets 22. Adjusting screws 24 and 25 are provided between the upper and lower boss portions 12 and 13 of the main frame 9 and the sub-frame 10, and have adjustment nuts 26 to

provide for aligning the sub-frame 10 vertically and laterally of the main frame 9.

The sub-frame 10, as best shown in Figure 1, comprises upper and lower fork-shaped portions 27 and 28 which each support a pair of ball bearing assemblies indicated at 29 and 30, respectively, for rotatably mounting an upper rotor member 31 and a lower rotor member 32 about a common vertical axis.

10 A pulley 33 is splined to the shaft portion 34 of the upper rotor 31 between the pair of bearing assemblies 29 laterally opposite the upper pulley 15 on the drive shaft 14. The pulleys 15 and 33 are provided with positive drive teeth 15 of gear form and of the same size and shape, and an endless belt 35 is trained about these pulleys. The belt 35, as shown, is formed with integral cleats or gear-shaped teeth 36 having positive driving engagement with the drive teeth 15 of the pulleys 15 and 33 to provide for the positive drive of the upper rotor 31 by the drive shaft 14. The lower rotor 32 has a pulley 37 keyed to the shaft portion 38 thereof between the pair of ball bearing assemblies 30. The pulley 37 is identical to pulley 33 and has positive drive teeth with which the cleats 38' of an endless belt 39, identical with belt 35, have positive driving engagement, and which belt 39 is trained over the pulley 16 which also has positive drive teeth to provide for the positive drive of the lower rotor 32. By virtue of the above construction, the upper and lower rotors 31 and 32 are caused to be driven in synchronism.

A spool cradle means generally indicated at 40 comprises spaced vertical side frame members 42 and is formed with reduced upper and lower end portions 43 and 44, respectively, which are journalled in ball bearing assemblies 45 and 46 in the upper and lower rotors 31 and 32. The cradle means 40 is thus supported with its vertical axis aligned with the common vertical axis of rotation of the upper and lower rotors 31 and 32, respectively. In this form of my invention the cradle means 40 is designed for the support of a pair of spools 47 and 48 disposed in vertical tandem relation, and which spools are rotatably mounted on shafts 49 and 50, respectively, extending between the side frames 42 and providing axes of rotation for the spools 47 and 48 extending transversely of and at right angles to the common vertical axis of rotation of the upper and lower rotors 31 and 32. The shafts 49 are removably mounted in the spool cradle means 40 by means of clamp plates 51 slidably mounted outwardly of the side frames 42, and which clamp plates are formed with keyhole slots 52 engageable in annular grooves at the ends of shafts 49 and 50 opposite the enlarged heads 53 thereof which engage boss portions 54 of the side frames 42. The clamp plates 51 are normally urged downwardly by coil springs 55 secured to the lower ends of the clamp plates 51 and anchored on pins 56 fixed to the side frames. The clamp plates 51 are formed with guide slots 57, and screws 58 threaded in the side frames 42 have the shank portions thereof extending through the slots 57 for guiding the vertical movement of the clamp plates 51. The clamp plates 51 at their upper ends are provided with laterally outwardly projecting lug portions 59 for moving the clamp plates upwardly to align the ends of the shafts 49 and 50 with the enlarged openings of the keyhole slots 52 against the force of springs 55, so that the shafts 49 and 50 may be removed by grasping the enlarged heads 53 and drawing the

shafts laterally outwardly of the cradle spool means 40. The spools 47 and 48 also have associated therewith brake means of suitable construction. The brake means referred to and as embodied in my present invention comprise brake drums 60 carried at one of the ends of each of the spools 47 and 48 and with which drums leather brake bands shown at 62 have frictional braking engagement. Each brake band 62 is suitably anchored at one end to an anchor pin 63 fixed to a side frame 42 and at its other end is connected at one end of a coil spring 64, and which coil spring 64 at its other end is connected to a crank arm 65 fixed to a tubular member 66. The tubular members 66 for the brakes for each spool are rotatably supported in coaxially aligned and abutting relation on a shaft 67 supported at its opposite ends in bosses 68 integral with the side walls 42. Sensing fingers 69 are secured to the tubular members 66, and are adapted to engage the periphery of the coils of wire on the spools 47 and 48 to control the degree of braking force of the brake bands 62 on the brake drums 60 by varying the tension of the springs 64 as a function of the diameter of the coil of wire on the spools. As described in the application last referred to, the coil springs 64 are effective for biasing the detector fingers 69 into engagement with the periphery of the coils of wire on the spools, and for frictionally engaging the brake bands 62 with the brake drums 60. The arrangement is such that as the diameter of the coil of wire on a spool decreases, the extent of the braking force applied by a coil spring 64 to a brake band 62 on a drum 60 decreases and provides for withdrawing out the wire from the spool under substantially uniform tension. The brake means for the upper and lower spools 47 and 48 are arranged with the brake drums 60 thereof disposed inwardly of opposite side frames 42 of the cradle means 40, which arrangement provides for the convenient disposal of the tubular members 66 carrying the sensing fingers 69 about the common supporting shaft 67 extending transversely between the side frames, and with the sensing fingers 69 disposed in laterally offset relation enabling the compact arrangement of the pair of spools 47 and 48 in the single spool cradle means 40.

The stranding machine in which my invention has been embodied is a three-wire strander providing for the stranding of wires 70, 71 and 72. The wire 70 is drawn from the coil of wire supported by the upper spool 47 through the upper rotor 31 which, as best shown in Figure 7, is provided with lengthwise extending bore 73 extending angularly outwardly from the hub portion 74 to the upper outer end of the shaft portion 34 of the upper rotor.

A conventional form of header post 75 is secured to the outer end of the shaft portion 34 of the upper rotor 31, and the header post at its outer end carries a three-wire header member 76 formed with conventional guide slots inwardly from the periphery thereof for the guiding of the wires to be stranded. The wire 71 from spool 48 extends downwardly through the opening 77 formed centrally in the bottom end wall of the spool cradle 40 and is trained about a plurality of guide rollers 78 carried in a member 79 supported on the lower rotor 32 in a transverse recess therein to provide for disposing the wire 71 in its upper vertical run outwardly of the periphery of the spool cradle means 40. The upper rotor 31 comprises, as best shown in Figure 5, a pair

of downwardly and outwardly extending arm members 80 and 81 formed along their upper edges with guide slots 82 and 83. The wire 71, as shown in the figure last referred to, is trained over a guide roller 83' at the outer lower end of slot 82 and an upper guide roller 84 at the upper end of the inwardly and upwardly extending slot 82. The wire 71 then passes through a vertically extending groove 85 at one side of the shaft portion 34 of the rotor 31 and through the header post 75 and header member 76. The upper rotor 31 is initially positioned so that the arm member 80 is disposed to align the slot 82 thereof with the member 79 and guide rollers 78 of the latter to guide the wire vertically from the lower rotor to the upper rotor.

The wire 72 is adapted to be drawn from a tail spool (not shown) but which is supported in a conventional manner below the sub-frame 10 either from the main frame 9 or other supporting structure. The tail spool from which the wire 72 is drawn is also preferably provided with an automatic brake means such as described for the spools 47 and 48, in order to provide for stranding of the three wires 70, 71 and 72 under uniform tension. The wire 72, as shown, extends vertically upwardly through bore 87 in the shaft portion 38 of the lower rotor 32 and is trained over a guide roller 88 journalled in the transverse recess of the lower rotor 32 and extends laterally and upwardly outwardly of the lower rotor and then about a guide roller 89 providing for disposing the wire 72 outwardly of the periphery of the spool cradle means 40 and diametrically opposite the wire 71. The wire 72, as best shown in Figure 5, is guided over a guide roller 90 at the lower outer end of the arm member 81 of the upper rotor 31, and passes through the guide slot 83 thereof to be guided by a roller 92 journalled adjacent the upper end of the angularly inwardly extending guide slot 83 for passage through a lengthwise extending bore 93 extending angularly inwardly and upwardly through the shaft portion 34 of the upper rotor 31 and thence to the header post 75 and the wire header 76. The strand formed by the three wires 70, 71 and 72 is, of course, reeled upon a suitable form of take-up reel supported above the machine, and such take-up is suitably driven for drawing the several wires through the paths above described. Referring to Figure 4, it will be seen that the guide rollers 84 and 92 are supported for rotation in the upper rotor member 31 by screws 94 and 95, respectively, and that the upper rotor member is provided with bores 96 and 97 extending inwardly of the hub portion and at right angles to the grooves 82 and 83 and through which bores the guide rollers 84 and 92 are adapted to be assembled in the upper rotor 31. In order to prevent the spool cradle means from rotating with the upper and lower rotors, I provide the cradle means 40 at the lower end thereof with a permanent magnet 100 suitably secured thereto and retained in position by the screw 102 in position immediately above the upper end of the lower rotor 32. As shown in Figures 1 and 3, a pair of magnet supporting arm members 104 are supported by brackets 105 at opposite sides and at the lower end of the U-shaped portion 18 of the sub-frame 10 and secured thereto as by the plurality of screws 106. The supporting arms 104 each provide for the support of a permanent magnet 107, and the magnets 107 are arranged in diametrically opposed relation with the poles thereof in alignment with the plu-

rality of poles of the permanent magnet 100. The magnets 100 and 107 provide a magnetic circuit for restraining the magnet 100 against rotation with respect to the fixed magnets 107 supported on the sub-frame 16 and prevent rotation of the spool cradle means 40. As shown, air gaps 108 are formed between the aligned poles of the magnets 100 and 107 to provide a path for the wires 71 and 72 in the rotation thereof about the cradle means 40 together with the upper and lower rotors 31 and 32.

It will be observed from the above detail description of one preferred form of my invention that I have provided a stranding machine comprising synchronously driven upper and lower rotors which eliminate the previously noted objectionable features of the previously known forms of tubular rotors of prior machines. The above described guide means for guiding the wire 72 from the tail spool of the apparatus, and together with the provision of the guide means in the lower rotor for the wire 71 from the lower spool 48 provides for disposing the wires outwardly of the periphery of the spool cradle means 40 in their travel to the upper rotor and the header post and wire header member at the upper end of the upper rotor 31. The arrangement of the permanent magnets 100 and 107 in aligned spaced relation of the poles thereof provides a path for the wires 71 and 72 in their rotation with the upper and lower rotors, and with the construction referred to provides for restraining the spool cradle means against rotation to prevent twisting of the wires withdrawn from the upper and lower spools in the cradle in the stranding thereof by the apparatus described.

Referring now to Figures 8 through 10, I have shown my invention embodied in a wire laying machine 110 substantially similar in most essential respects to the machine first above described, except that gear means indicated generally at 111 is provided for driving the upper and lower rotors 113 and 114, respectively, in synchronism. The upper rotor 113, as shown, is journaled in a pair of vertically spaced ball bearing assemblies 115 supported in the arms 116 of frame means partially shown at 117, and the lower rotor 114 is also journaled in a pair of vertically spaced ball bearing assemblies 118 supported in arms 119 of the frame 117. A gear 120 is splined in the shaft portion of the rotor 113 and is disposed intermediate the pair of ball bearing assemblies 115, and a gear 122 identical with gear 120 is secured to the lower rotor between the ball bearing assemblies 118. The gears 120 and 122 have meshing engagement respectively with gears 123 and 124, secured to a vertically extending drive shaft 125 which may be rotated in any desired manner, for example, by suitable connection with an electric motor. The gears 123 and 124 are of identical construction, so that upon rotation of the shaft 125 the upper and lower rotors 113 and 114 are caused to be driven in synchronism.

As before, a suitable cradle, shown at 125', is journaled at its upper end in a ball bearing assembly 126 in the upper rotor 113, and at its lower end in a ball bearing assembly 128 in the lower rotor 114. The cradle 125' provides for the rotatable support of an upper spool 129 and a lower spool 130, and a third spool 132 is rotatably supported on a bracket 133 suitably secured to the supporting frame for the machine. The machine 110 is also designed for the stranding of three wires 135, 136 and 137 drawn re-

spectively from the spools 129, 138 and 132. The wire 135 is drawn from the coil of wire carried by the upper cradle spool 129 through the upper end of the cradle 125'. A pair of hardened annular steel inserts 139 are mounted in a bore at the upper end of the cradle 125' through which the wire 135 passes. The wire 135, as best shown in Figure 10, then passes through an angularly offset bore 140 in the upper rotor, an opening in a guide plate member 142 fixed to the upper rotor 113 immediately below the lower ball bearing assembly 115 and thence through a groove 144 to the wire laying head member 145 mounted at the upper end of the upper rotor 113.

The wire 136 from the lower cradle spool 138 passes downwardly through a bore in the lower end of the cradle 125' in which hardened annular steel inserts 145 are mounted. The wire 136 is then guided about rollers 146 suitably secured in a transverse opening in lower rotor 114, then passes vertically upwardly to a guide roller 148 carried at the outer end of the downwardly and outwardly projecting arm 149 of the upper rotor 113, and then through another opening in the guide plate 142 and through the vertically extending groove 150 to the wire laying head 145.

The wire 137 from the tail spool 132 is drawn through the lower end of the lower rotor 114 through hardened steel inserts 152 in a bore in the lower end of the latter, and is then trained over a guide roller 153 carried by the lower rotor 114 diametrically opposite the rollers 146 for the wire 136, thence vertically upwardly to the guide roller 154 carried at the outer end of an arm 155 diametrically opposite arm 149 of the rotor 113, and thence through the guide plate 142 and through still another opening in the lengthwise extending groove 156 of the upper rotor 113 to the wire laying head 145.

The cradle 125', as in the previous embodiment, has a permanent magnet 160 secured to the lower end thereof and with respect of which a pair of permanent fixed magnets 162 are arranged to provide for restraining the cradle 125' against rotation. The permanent magnets 162 provide, with the permanent magnet 160, gaps or passageways 163 in which the wire 136 from the lower cradle spool 138, and the wire 137 from the tail spool 132 pass in the rotation of the upper and lower rotors. The permanent magnets 162 may, for example, be mounted in fixed relation on the frame of the machine in the manner described in connection with the embodiment of my invention shown in Figures 1 through 7.

The operation of the apparatus of Figures 8 through 10 is the same as that previously described, and it will be seen that by the provision of identical gears 120 and 122 for the upper and lower rotors 113 and 114, having meshing engagement with identical gears 123 and 124 carried by the drive shaft 125, the upper and lower rotors are caused to be driven in synchronism to effect laying of the three strands of wire 135, 136 and 137.

The essential difference between the machine shown in Figures 8 through 10 over that of the embodiment first described resides in the provision of the positive gear drive means for driving the upper and lower rotors in synchronism, and if desired the other parts of the apparatus may be identical to those described in the first embodiment, in view of which the supporting frame structure for the several parts of the machine 110 have not been illustrated in detail in connection with the Figures 8 through 10. The two embodi-

ments of my invention herein disclosed embody different forms of positive drive means for synchronously driving the upper and lower rotors, and it will be understood that my invention is not limited to the specific forms of such drive means for other forms thereof will readily suggest themselves to those skilled in the art.

While I have shown and described what I consider to be preferred embodiments of my invention, it will be understood that various modifications and rearrangements may be made therein without departing from the spirit and scope of my invention.

I claim:

1. In a wire stranding machine, the combination of frame means, upper and lower rotor members journalled in spaced vertical relation on said frame means about a common vertical axis, cradle means extending between and journalled at its opposite ends in said rotor members and with its lengthwise axis aligned with the axis of rotation of said rotor members, spools adapted to carry coils of wire mounted for rotation in said cradle means with their axes extending transversely of the lengthwise axis of said cradle means, guide means for said rotor members for guiding a strand of wire from one of said spools through said lower rotor and vertically upwardly to said upper rotor outwardly of the periphery of said cradle means, drive means for said rotor members for driving the latter in synchronism, first magnetic means fixed to said cradle means, and second magnetic means supported in fixed relation on said frame means in alignment with said first magnetic means for preventing rotation of said cradle means, said second magnetic means being spaced from said first magnetic means to provide a gap therebetween for passage of said strand of wire from said lower rotor to said upper rotor.

2. In a wire stranding machine, the combination of frame means comprising a main frame, and a sub-frame supported on said main frame to extend laterally of the latter, upper and lower rotor members journalled in spaced vertical relation on said sub-frame about a common vertical axis, cradle means for carrying spools of wire extending between and journalled at its opposite ends of said rotor members and with its lengthwise axis aligned with the axis of rotation of said rotor members, and drive means for said rotor members comprising a drive shaft extending parallel with the axis of rotation of said rotor members and journalled in said main frame, and means between said drive shaft and said rotor members for driving the latter in synchronism.

3. In a wire stranding machine, the combination of frame means comprising a main frame, and a sub-frame supported on said main frame to extend laterally of the latter, upper and lower rotor members journalled in spaced vertical relation on said sub-frame about a common vertical axis, cradle means for carrying spools of wire extending between and journalled at its opposite ends of said rotor members and with its lengthwise axis aligned with the axis of rotation of said rotor members, and drive means for said rotor members comprising a drive shaft extending parallel with the axis of rotation of said rotor members and journalled in said main frame, means between said drive shaft and said rotor members for driving the latter in synchronism, and means between said sub-frame and said main frame for adjusting said sub-frame laterally of said main frame.

4. In a wire stranding machine, the combination of frame means, a pair of rotor members journalled in spaced apart relation for rotation about a common axis on said frame means, cradle means for carrying spools of wire journalled coaxially of the axis of rotation of said rotor members, guide means for guiding a wire from at least one of the spools of wire in a substantially cylindrical path outwardly of said cradle means and toward one end of said machine, a wire laying head at said one end of said machine for laying the wires from said spools over each other, drive means for driving said rotors in synchronism, and means for preventing rotation of said spool cradle means with said rotor means.

5. The machine of claim 4 characterized by the provision of means for supporting an additional spool of wire at the end of said machine opposite said one end thereof, and additional guide means for said rotor members for guiding the wire from said last named spool of wire diametrically opposite of and in the cylindrical path of the first mentioned wire.

6. In a wire stranding machine, the combination of frame means, a pair of rotor members journalled in spaced apart vertical relation for rotation about a common vertical axis on said frame means, cradle means for carrying spools of wire journalled coaxially of the vertical axis of rotation of said rotor members, guide means for said rotor members for guiding a wire from at least one of the spools of wire of said cradle means in a substantially cylindrical path outwardly of said cradle means and toward one end of said machine, a wire laying head at said one end of said machine for laying the wires from said spools over each other, drive means for driving said rotors in synchronism, and means for preventing rotation of said spool cradle means with said rotor means.

7. The machine of claim 6 characterized by the provision of means for supporting an additional spool of wire at the other end of said machine, and additional guide means for said rotor members for guiding the wire from said last named spool of wire diametrically opposite of and in the cylindrical path of the first mentioned wire.

8. The stranding machine of claim 4 characterized by said drive means comprising a drive shaft extending parallel with the axis of rotation of said rotor members, and gear means between said rotor members and said drive shaft for effecting rotation of said rotor members by said drive shaft.

55. 9. The wire stranding machine of claim 4 characterized by said drive means comprising a first pair of like pulleys secured one to each of said rotor members, a drive shaft extending parallel with the axis of rotation of said rotor members, a second pair of like pulleys one secured to each of said rotor members, said pulleys having uniformly spaced drive teeth, and belt means between one each of said first and second pairs of pulleys and having cleats for engaging the drive teeth of said pulleys whereby said rotor members are caused to be driven in synchronism.

10. The stranding machine of claim 6 characterized by said drive means comprising a drive shaft extending parallel with the axis of rotation of said rotor members, and gear means between said rotor members and said drive shaft for effecting rotation of said rotor members by said drive shaft.

11. The stranding machine of claim 6 characterized by said drive means comprising a first

pair of like pulleys secured one to each of said rotor members, a drive shaft extending parallel with the axis of rotation of said rotor members, said pulleys having uniformly spaced drive teeth, and belt means between one each of said first and second pulleys and having cleats for engaging the drive teeth of said pulleys whereby said rotor members are caused to be driven in synchronism.
